UNITED STATES PATENT OFFICE.

SETH WHITE PAINE, OF ROCHESTER, NEW YORK.

CUTTING ATTACHMENT FOR CHECK-BOOKS.

SPECIFICATION forming part of Letters Patent No. 367,230, dated July 26, 1887.

Application filed April 18, 1887. Serial No. 235,232. (No model.)

To all whom it may concern:

Be it known that I, SETH WHITE PAINE, a citizen of the United States, residing at Rochester, in the county of Monroe and State of New York, have invented new and useful Improvements in Cutting Attachments for Check-Books, of which the following is a specification.

My present invention relates to a cutting attachment for that class of check, draft, or receipt books in which a series of independent blanks and stubs are bound in a single cover and separated by longitudinal spaces between the consecutive stubs and checks.

15 The invention consists of a transverse cutter or straight-edge adjustably mounted on or attached to a support arranged in a longitudinal space between two consecutive check, draft, or receipt blanks, and capable of being 20 moved in line with its support to and from the transverse division-line between each blank and its stub, whereby all the checks or other blanks can be accurately, uniformly, and neatly severed from their stubs, leaving the stubs of 25 uniform length and enabling them to be readily disengaged from beneath the cutter and turned back after the check, draft, or receipt has been torn off.

In the particular construction illustrated in 30 the annexed drawings, Figure 1 is a perspective view of a check-book having two independent blanks and stubs to each page, said blanks separated by a longitudinal space, and showing my improved adjustable cutter applied for use. Fig. 2 is a plan of one of the 35 pages, showing two checks and stubs, with the cutter and its support removed. Fig. 3 is a perspective view of the cutter and its support detached. Fig. 4 is a longitudinal section on the line $x-x$ of Fig. 1, showing the cutter and its support in place. Fig. 5 is a similar section illustrating a modification in the cutter-support or means for attaching it to the book.

40 45 The letter A designates the cover of a check-book, B the checks, and C the stubs. In this check-book the consecutive blanks of each page are separated by a longitudinal space, a , extending the whole length of each check and 50 its stub. This space a may be of any sufficient width to permit the passage of a support,

D, for a cutter or straight-edge, E, that extends across the several checks of each page.

In the form of construction shown each page of the book consists of two independent blanks 55 and their stubs, with a central longitudinal space, a , and each blank may have a transverse line, b , marked thereon to indicate the place of separation between the check and its stub. The cutter E is mounted adjustably 60 on its support in such a manner as to rest transversely on the blanks at about the junction of the checks and stubs, and so as to be capable of movement to and from the line b , indicating the point where they are to be torn 65 apart.

I prefer to employ a cutter-support consisting of an arm, D, of wire, flat metal, or other elastic or flexible material. One end of this arm D may be spread or extended, as shown 70 at c , and secured by cement or otherwise to the inner side of the back cover of the book or to a back fly-leaf. This arm D is located in the space a , and is slightly bent or curved to project diagonally toward the stubs. The 75 free end of the arm D is passed through a loop or eye, d , formed on or attached to the cutter E, and the latter is thereby arranged so as to be moved back and forth on its supporting-arm between stops or shoulders $e-e$, formed thereon, 80 as shown.

When it is desired to detach a check, the cutter or straight-edge E is adjusted to bring its outer edge into coincidence with the line b , and is then pressed down firmly onto the 85 leaf with the fingers of the left hand, while the check is grasped with the fingers of the right hand and torn off transversely along the edge of the cutter. By then moving the cutter along its support slightly to the right the edge 90 of the stub will be uncovered, so it can be turned back. If the cutter is carefully adjusted to the lines b in succession, the several stubs will be left of equal length, notwithstanding the 95 "draw" of the leaves on opening the cover, and the last check, draft, or receipt will be severed just as neatly as the first.

If desired, the ends of the cutter or straight-edge E can be slightly turned down, or provided with narrow flanges $f-f$, to assist in 100 keeping the cutter and the leaves in proper relative position.

Instead of mounting the cutter E on a supporting arm D, as shown in Figs. 1, 3, and 4, it may be attached to the book by means of one or more elastic bands, F, passed through 5 an eye or eyes, g, on the underside of the cutter and extended through the longitudinal space a to the opposite ends of the back, to which the ends of the band or bands F can be secured in any suitable manner, as shown in 10 to Fig. 5.

It is obvious that the elastic band or bands F will draw the transverse cutter E down in close contact with the faces of the upper blanks, and yet allow it to be moved to the right and 15 left to adjust it to the lines b, or to permit the disengagement and backward turning of the stub of the severed blank.

Although I have shown a check-book having only two blanks to each page, it is evident 20 that a larger book, with three or more blanks, can be adapted to the cutter E in like manner, a longitudinal space a being arranged between the several blanks of each page, and a cutter-support, as arm D or band F, located 25 in each longitudinal space. In this event the

cutter E will have a loop or eye d for each elastic arm, or an eye g for each elastic band. When all the check, draft, or receipt blanks have been exhausted, the cutter and its support or supports can be easily detached and 30 repeatedly applied to and used with other books of like character.

What I claim as my invention is—

1. The combination, with a check, draft, or receipt book having blanks separated by a longitudinal space, of a cutter-support located in 35 said space, and a transverse cutter or straight-edge adjustable on said support, substantially as described.

2. As a new article of manufacture, a cutter 40 or straight-edge adjustably mounted on a detachable arm having stops to limit the movement of said cutter or straight-edge, substantially as described.

In testimony whereof I have affixed my signature in presence of two witnesses.

S. WHITE PINE.
